UNITED STATES PATENT OFFICE.

ALBERT D. PENTZ, OF LYNN, MASSACHUSETTS, ASSIGNOR TO GENERAL ELECTRIC COMPANY, A CORPORATION OF NEW YORK.

METHOD OF SHOEING PERMANENT MAGNETS.

1,192,680.

Specification of Letters Patent. Patented July 25, 1916.

Application filed September 5, 1914. Serial No. 860,349.

To all whom it may concern:

Be it known that I, ALBERT D. PENTZ, a citizen of the United States, residing at Lynn, in the county of Essex, State of Massachusetts, have invented a certain new and useful Method of Shoeing Permanent Magnets, of which the following is a specification.

My invention relates to attaching means for permanent magnets, and particularly to attaching shoes for electric meter magnets.

The object of my invention is to provide a novel and improved method of shoeing permanent magnets, and in particular a novel and improved method of shoeing the permanent damping magnets of electric motor meters.

More specifically, the object of my invention is to provide a simple, convenient, inexpensive, and positive method of securing an attaching shoe to the permanent magnets of an electric motor meter.

Considerable difficulty has heretofore been experienced in satisfactorily securing an attaching shoe to the damping magnets of an electric meter. As is well understood in the art, the manner of attaching the shoe to the magnet must not affect the magnetic characteristics and properties of the magnet, and, since the magnet is of hardened steel, the ways in which a shoe may be securely and satisfactorily attached thereto without injuring the magnetic properties of the magnet are limited. Heretofore, it has been generally customary to provide the shoe with long toes which are bent about the magnet so as to firmly clasp the same. The toes are manually hammered around the material of the magnet, and, first on account of the peculiar configuration of a meter magnet, but more on account of the inherent nature of a hammer blow as hereinafter explained, a secure engagement of the toes of the shoe with the magnet is difficult, and consequently the magnet frequently becomes loose in the shoe. Furthermore, it has heretofore been the practice to bend the toes of the shoe about the magnet by hand in order to obtain results in any degree satisfactory, and this operation is objectionably expensive.

I have devised a novel and improved method of shoeing a permanent magnet whereby the shoe is firmly and positively secured to the magnet, so that even after un-

usually rough treatment the magnet is firmly held to the attaching shoe. I have also devised a simple, novel and economic type of shoe which serves to hold a permanent magnet of special sectional configuration securely fastened thereto. The method of shoeing and the form of the magnet and shoe are further of such a character that the shoe can be readily applied to the magnet by mechanical means at a nominal cost.

The novel features of my present invention which I believe to be patentable are definitely indicated in the claim appended hereto.

My improved method of shoeing a permanent magnet and the advantages and novel character of the same will be understood from the following description taken in connection with the accompanying drawings, in which:

Figure 1 is a partial perspective view of a machine designed to carry out my novel method of shoeing a permanent magnet; Fig. 2 is a sectional view taken on the line 2—2 of Fig. 1 showing a detail of the machine and illustrating the means for forcing the shoe under pressure into intimate contact with the magnet; Fig. 3 is a view of a pair of meter magnets secured to an attaching shoe in accordance with the principle of my invention; Fig. 4 is a partial sectional view on line 4—4 Fig. 3, of one of the magnets and the shoe shown in Fig. 3; Fig. 5 is a view of a pair of meter magnets of modified design secured to an attaching shoe in accordance with the principle of my invention; Fig. 6 is a view of one of the magnets shown in Fig. 5; Fig. 7 is a section on the line 7—7 of Fig. 5 before the shoe has been forced under pressure into its clamping position; Fig. 8 is a section on the line 7—7 after the shoe has been forced under pressure into its clamping position; and Fig. 9 is a detail explanatory view.

Heretofore, it has been generally customary to make a meter magnet with rounded edges, as indicated in dotted lines in Fig. 9 of the accompanying drawings. The attaching shoe for such a magnet is provided with long toes which are manually hammered over the rounded edges of the magnet. In accordance with my present invention, the magnet is given a substantially trapezoidal section, as shown in Figs. 4, 7, 8 and 9 of the drawings. This peculiar sectional con-

figuration of the magnet lends itself to a very simple and most effective method of shoeing. The shoe, in accordance with my invention, has short relatively heavy lugs 5 instead of the former long relatively thin toes, and these lugs are squeezed under a considerable stress, for example in the neighborhood of twenty tons, into intimate contact with the magnet.

10 As before stated, the toes of the attaching shoe have heretofore been hammered about the magnet. A hammer blow is sudden and always permits the hammered metal to rebound. Hence, it is extremely difficult, 15 if not impossible, to effect an intimate and secure engagement between the shoe and magnet by a hammering action. A squeeze differs materially from a hammer blow, particularly in that with a squeeze there is an 20 instant of rest under compression during which the metal substantially flows into the condition under which it exists when compressed, so that after the pressure is removed the molecules of the metal have readjusted themselves to the compressed condition, and there is consequently little or no 25 tendency to rebound.

My novel and improved method of shoeing a permanent magnet thus consists in 30 squeezing the shoe onto the magnet with a pressure of several tons to the square inch, and maintaining the state of compression between the shoe and the magnet, occasioned by such squeezing action, for an appreciable 35 length of time, and until the metals of the shoe and magnet have adjusted themselves to the new molecular conditions occasioned by the squeeze.

Reference to the accompanying drawings 40 will explain more clearly my present invention.

Fig. 3 illustrates a pair of permanent magnets 10 secured to a shoe 11 in accordance with the principle of my invention. 45 The permanent magnets 10 are of a well known design employed in electric motor meters for damping the rotation of the movable element. The magnets are adapted to be securely fastened to the shoe 50 11 in accordance with the principle of my invention, and are then suitably mounted in the meter by means of the screw-threaded holes 16 in the shoe, in such a manner that the damping disk of the meter is operatively 55 positioned in the air gaps of the magnets in the well known way.

The shoe 11 is cast of composition metal, which, as is well known, is considerably softer than the hardened steel of the magnets. In accordance with my present invention that portion of each permanent magnet to which the shoe is attached is of substantially trapezoidal cross-section. This will be clearly seen by reference to Fig. 4 60 of the drawings, wherein the magnet 10 is

represented as having a substantially quadrilateral cross-section with two sides substantially parallel and the other two sides non-parallel and converging toward each other. The shoe has a base portion 12 which is adjacent the longer of the two parallel sides of the magnet and which is provided with projections 13 in engagement with this side of the magnet. It will be observed that the projections 13 are the only part of the base 70 portion 12 of the shoe in actual contact with the magnet and that the remainder of the base portion extends substantially parallel to the longer of the two parallel sides of the magnet, but is separated therefrom by a 75 narrow air space. The shoe is cast of composition metal, and is secured to the magnet in its cast condition without any previous machining. Since it is substantially impracticable to cast the shoe so that the base portion 80 12 has a perfect plane surface, it is necessary to provide the projections 13, which form four points of support for each magnet and serve to satisfactorily position the magnet with respect to the shoe, regardless of any irregularities upon the adjacent 85 surfaces of these two members. The base portion 12 of the shoe is provided with a central boss 14 which determines the minimum distance between the two magnets 10 90 95 as will be clearly seen in Fig. 3 of the drawings.

The shoe 11 has integrally attached thereto two pairs of lugs 15, each pair of lugs being adapted to firmly secure one of the 100 permanent magnets 10 to the shoe in accordance with the principle of my present invention. It will be observed that the lugs 15 are designed to engage with the two non-parallel sides of the magnet. 105

In shoeing the magnet in accordance with my novel and improved method, the magnet is first placed in its proper position with respect to the shoe. The magnet and shoe, thus assembled, are placed in a power 110 press, such for example as is represented in Figs. 1 and 2 of the drawings, and the press is then operated to squeeze or force the lugs 15 into very intimate contact with the non-parallel sides of the magnet under 115 a pressure of several tons to the square inch.

The press shown in Figs. 1 and 2 has a central alining member 20, which is adapted to extend through the air gap between the 120 poles of each of the two magnets 10, and which serves as a centering axis for the magnets and the shoe. The alining member 20 is mounted upon a rockable plate 29, which latter also carries the lower die 27 125 of the press. The plate 29 also has secured thereto three posts 31 and 32. The post 32 is adapted to enter the space between the ends of the assembled magnets and serves to properly and accurately determine the 130

distance between the two magnets. A post 31 is positioned on each side of the center post 32, and each post 31 is adjacent the outside surface of one of the magnets 10. 5 Bolts 30 are secured to a base 34, and extend through holes in the ends of the plate 29. Each bolt 30 is provided with an enlarged head, between which and the plate 29 a spring 28 is confined. The base 34 is slidably mounted in guides 23 of a stationary supporting member. A hand operated lever 21 has a fixed pivot 19, and is connected by linkage 18 to the slideable base 34. A wedge 17 is mounted on the linkage 18, and is 10 adapted to be forced by movement of the lever 21 against a block 22 bolted to the base 34. Movement of the lever thus operates to move the base 34, through the engagement of the wedge 17 with the block 22, thereby carrying the plate 29 and the assembled magnets and shoe toward a stationary block 24. The stationary block 24 has 15 wear plates 33 which are adjacent the back of the shoe 11. When the slideable base is moved toward the block 24 the assembled magnets and shoe are firmly and accurately secured between the posts 31 and the wear plates 33, and are thus ready for the squeezing 20 operation. 25 The part of the press above described, called the fixture, is suitably supported by a rigid base member and springs of great rigidity to take up the shock of and to cushion the great pressure to which the fixture is subjected during the squeezing operation.

Since the construction of the power press forms no part of my present invention, I have merely indicated in Figs. 1 and 2 only 30 those essential elements of the construction necessary for a clear understanding of my novel method of shoeing a permanent magnet.

When the magnets and shoe are properly positioned in the press and firmly held between the posts 31 and the wear plates 33, a vertical plunger 25 carrying the upper die 26 is forced down upon the shoe, and the lugs 15 are squeezed into intimate contact with the magnets between the upper die 26 and the lower die 27, as will be best understood by reference to Fig. 2 of the drawings. The pressure applied during this squeezing operation is in the neighborhood of 20 tons and the metal of the shoe is virtually crushed into very intimate engagement with that of the magnets. The shoe and magnets are maintained in a state of compression occasioned by the squeezing action for an appreciable length of time, for example, one, two or more seconds, and until the metals of the shoe and magnets have had sufficient time to prevent material rebound of the metal of the shoe after the pressure has been removed.

The entire operation is carried on under normal temperature conditions, that is at ordinary room temperature, and the squeezing of the lugs of the shoe into intimate contact with the magnet is effected by pressure alone, and without the application of any heat for softening the metal of the shoe. 70

The manner in which the lugs 15 engage the trapezoidal cross-section of the permanent magnets will be evident from an inspection of Fig. 4 of the drawings. It will be observed from Fig. 3 of the drawings that the central boss 14 acts to prevent lateral movement of the magnets toward one another and that the elbow 17 of each magnet, which is held firmly clamped between the lugs 15, prevents movement of the magnets away from one another. In magnets which have not a curved elbow like the magnets shown in Fig. 3, I have found it advisable to impart an irregularity to the surface of the magnet to prevent any tendency of relative lateral movement between the shoe and magnet. This feature of my invention will 85 be understood by reference to Figs. 5, 6, 7 and 8 of the accompanying drawings. In these figures two magnets 35 are shown secured to a shoe 36 in accordance with the principle of my invention. The lugs 37 of 90 the shoe are forced into intimate contact with the non-parallel sides of the magnet in exactly the same manner as heretofore described. Each magnet has an irregularity or indentation 39 on its surface. When the lugs are forced under pressure into contact with the sides of the magnet, the metal of 95 the lugs is forced into the irregularities 39, whereby relative lateral movement of the shoe and magnet is prevented.

Since the metal of the shoe is considerably softer than that of the magnet, the former will be forced to conform to the configuration of the latter, so that by the powerful squeezing action to which the assembled shoe and magnets are subjected the metal of the shoe will be literally forced into any depressions in the surface of the magnets. The irregularity in the surface of the magnet is hence preferably in the nature of a notch which can be cut or struck in the magnet in any suitable way and into which the metal of the shoe is forced by the squeezing action.

It will of course be understood that more than one irregularity may be imparted to the surface of the magnet, the important condition to be fulfilled being that the irregularity, or irregularities, be of such a character that the metal of the shoe is forced 125 into the irregularity to prevent any possible relative lateral movement of the magnet with respect to the shoe.

The shoe 36 is provided with a projection in the nature of a ridge 38, similar in func- 130

tion to the projections 13, so that the ridge is the only part of the surface of the base portion of the shoe 36 in actual contact with the magnet. Screw-threaded holes 40 and 5 41 serve to mount the shoe and attached magnets in the meter.

The trapezoidal section which I give the permanent magnets in carrying out my invention results in a substantial saving in the 10 material of the magnet for the same effective damping. For example, consider the two types of magnets illustrated in Fig. 9 of the drawing. The effective damping zone of the rounded-edge magnet, partially represented in dotted lines, is indicated by the line A. The effective damping zone of the magnet of trapezoidal section, shown in full lines, is indicated by the same line A. The rounded-edge magnet and the magnet of 20 trapezoidal section thus produce the same effective damping and the saving in material effected by the application of my invention amounts substantially to the area of the corners indicated by reference letter b. The 25 areas a must obviously be subtracted from the areas b to accurately determine the actual saving in material, but it will be evident that the area a is very considerably smaller than the area b, and hence that the saving 30 in the material of the magnet is very substantial.

It will be evident from the foregoing description and explanation that I have provided a simple and effective method of shoeing a permanent magnet. By the application 35 of my invention a very considerable economy is also effected in the amount of material required for the shoe, since the

amount of material in a shoe designed in accordance with the principle of my invention 40 is considerably smaller than in a shoe with long toes, such as heretofore generally employed. Furthermore, where such long members as the toes of the former shoes are bent about a magnet to clamp the same, 45 the degree of bending, that is the angle through which a toe is bent, is very large, and the shoe must be made of a relatively high grade of alloy to withstand such excessive bending. In the case of my method of 50 shoeing and novel construction of shoe the attaching lugs are short, and the degree of bending is relatively small, so that a much lower grade of alloy may be employed for the shoe. 55

What I claim as new and desire to secure by Letters Patent of the United States, is:—

The method of securing a shoe having extending lugs to a permanent magnet which consists in squeezing the lugs of the shoe 60 under normal temperature conditions onto the magnet with a pressure sufficient to virtually crush the lugs of the shoe into intimate contact with the magnet, and maintaining the state of stress between the lugs 65 of the shoe and the magnet occasioned by such squeezing action for a length of time sufficient to prevent material rebound of the lugs from the magnet after the pressure has been removed. 70

In witness whereof, I have hereunto set my hand this 2nd day of September, 1914.

ALBERT D. PENTZ.
